UNITED STATES PATENT OFFICE.

FREDERICK L. FULLER, OF DAYTON, OHIO, ASSIGNOR TO THE NATIONAL CASH REGISTER COMPANY, OF DAYTON, OHIO, A CORPORATION OF OHIO, (INCORPORATED IN 1906.)

AUTOGRAPHIC REGISTER.

1,202,825.

Specification of Letters Patent.

Patented Oct. 31, 1916.

Application filed July 19, 1913. Serial No. 779,918.

To all whom it may concern:

Be it known that I, FREDERICK L. FULLER, a citizen of the United States, residing at Dayton, in the county of Montgomery and 5 State of Ohio, have invented certain new and useful Improvements in Autographic Registers, of which I declare the following to be a full, clear, and exact description.

The present invention relates to autographic devices and has more particular relation to that class of autographic devices which comprises a machine capable of handling a plurality of record strips to receive written records thereon and to be mechanically fed from the machine to form a sales slip and separate record of transactions.

A large number of autographic devices have been designed heretofore employing various forms of feeding devices, but it is 20 one of the objects of the present invention to provide an improved form of feeding device and particularly a feeding device which is adapted to handle large sized record strips.

25 In autographic machines employing feeding devices heretofore designed it was found practically impossible to feed a plurality of record strips, all of which had previously been printed and to feed the strips simultaneously so as to cause the printed forms on the various strips to register properly to permit of a perfect record being made on the several strips. In many well known devices of this type a written record is made

35 on the original or top strip of a series and this record is transferred to any desired number of duplicate strips placed beneath the original record strip and having transfer paper or other transfer material interposed between the various strips. Many well known forms of feeding devices are satisfactory where the duplicate and triplicate strips are merely in a blank form, but where it is desired to have the duplicate

45 and triplicate strips printed with the same form as the original strip, it is found very difficult to provide a feeding mechanism capable of giving an exactly equal feed to all of the plurality of strips.

50 The principal object of the present invention is to provide an efficient feeding de-

vice for giving an equal feed to a number of previously printed record strips.

With these and incidental objects in view, the invention consists in certain novel features of construction and combinations of parts the essential elements of which are set forth in appended claims, and a preferred form of embodiment of which is hereinafter described with reference to the drawings 55 which accompany and form part of this specification.

Of said drawings:—Figure 1 is a left profile of the machine. Fig. 2 is a rear end view of the machine showing the operating 65 connections for moving the feeding table. Fig. 3 is a detail view of the operating connections for controlling the clamping devices. Fig. 4 is a detail in right elevation of a special manipulative device and connections for moving the slide 16 independently 70 of an operation of the machine. Fig. 5 is a detail view of one form of supporting means for the roll of record material. Fig. 6 is a detail view of the operating connections and 75 full stroke mechanism. Fig. 7 is a left profile of the machine showing a modified form of supporting means for the rolls of record material. Fig. 8 is a cross section of the machine showing the same form of 80 supporting means as shown in Fig. 7 and partly in cross section. Fig. 9 is a detail view of a spring for preventing retrograde movement of the record strips.

In the form of autographic register shown 85 in the present application, the machine is designed to handle three rolls of record material which, in the present instance, are strips of paper which are fed from the supply rolls. Each of the three record strips 90 has printed on one side thereof a form which is adapted to be filled out in the use of the machine. The three strips of record material are printed with exactly the same form and information so that the three 95 strips represent exact duplicates of each other. The strips are adapted to be led from the rolls of record material, which are suitably supported in the base of the machine, to a writing platform where they are adapted 100 to receive the written entries. Transfer paper is employed in the present machine

and interposed between the different strips of paper so as to transfer to the duplicate strips all of the information written upon the original strip.

5. A feeding mechanism for feeding the record strips after the entry has been made is provided in the present machine and comprises a table slidably mounted beneath the writing platform, and carrying a clamping device which normally clamps the strips of paper at the top edge of the printed form across the rear of the machine. Upon the operation of a main operating mechanism, the table is projected rearwardly from the machine and the three strips of record material are drawn equal distances from the machine. Upon the continued operation of the main operating mechanism the clamping device is released and the table restored to normal position, the strips in the meantime remaining in the position to which they were drawn by the movement of the table. Upon the complete return of the feeding table to normal position the clamping devices will again become effective to clamp the record strip at the top of the next blank form appearing on the same. The portion of the record strip which constitutes a complete form on each of the three strips of paper is adapted to be severed from the strips, thereby forming triplicate slips showing the complete record of the transaction. To facilitate the severing of the portions of the record strips which are thus fed from the machine the upper member of the clamping device in the feeding table is beveled to form a cutting edge, and the portion of the record strip which is fed from the machine may be severed from the main strip by drawing it taut across the cutting edge.

The rolls of record material are indicated by the reference numerals 1, 2 and 3 in Figs. 1 and 7. The record strips are, as shown in Fig. 1, led from the rolls 1, 2 and 3 forwardly toward the operator and over a series of guiding rollers 4, one of which is provided for each strip and mounted in the casting of the machine at the forward edge of the same. The strips are then passed from the rollers 4 over a writing bed or platform 35 which forms a supporting surface for an entire form appearing on the record strip so as to form a rigid writing platform. The record strip after being passed rearwardly over the writing platform 35 passes beneath a clamping member 6 mounted on the rear end of a sliding frame 5, slidably mounted beneath the writing platform 35 and adapted to slide in guideways formed in the frame 60 of the machine.

Mounted along the right hand edge of the machine as shown in Fig. 8 is a receptacle 7 adapted to contain a supply of carbon paper or any other desired form of transfer mate-

rial. In the present instance the roll of 65 carbon paper should comprise a double sheet so that one section of the same may be placed between the original and duplicate strips and one between the duplicate and triplicate surface so as to facilitate the transfer of a written entry from the original to both the duplicate and triplicate strips. The carbon paper is adapted to be placed between the strips and pass across the entire writing platform 35 and is clamped to the frame of 70 the machine at the left hand side of the same to prevent any accidental displacement of the carbon paper. The carbon paper is clamped at the left hand side of the machine by a clamping member 36 shown in 75 Figs. 2 and 6 and comprising a rod pivoted at one end at 37 to the frame of the machine and formed at the other end with a hooked portion adapted to co-act with a headed pin 38 to hold the carbon paper in 80 proper position.

In the normal condition of the machine the clamping member 6 is in the position shown in Figs. 1, 3 and 7. In this position it will readily be seen that the ends of the 90 record strips will be held clamped to the frame 5. The operating means is adapted to project the frame 5 rearwardly of the machine that is, to the left as shown in the three figures just mentioned in the following manner: A main operating lever 17 is provided which lever is fast to the left hand end of a rock shaft 8 supported by standards formed on the base of the machine. Fast to the shaft 8 is a segment 9 projecting upwardly, and formed on its upper edge with rack teeth adapted to mesh with a pinion 10 fast on an oscillatory shaft 29. Carried by the shaft 29 is a pair of small gears 12 and 13 which normally mesh respectively with a 100 pair of racks 14 and 15 formed on the under side of the sliding frame 5. Upon the movement of the handle 17 in a clockwise direction the pinion 10 and gears 12 and 13 will be rotated in a counter-clockwise direction 105 and thereby project the frame 5 to the left as shown in Figs. 1, 3 and 7. This, it will readily be seen, will draw the record strips to the left as shown in said figures and thereby effect a movement of the record 110 material to the desired extent.

The clamping member 6 is carried by a pair of arms 25 fast on a rock shaft 24 supported by the frame 5. As shown in Fig. 3 the shaft 24 also has fast upon it a plate 120 23 carrying a pair of anti-friction rollers 22 and 34. Co-operating with the plate 23 and its rollers 22 and 34 is a sliding bar 16 slidably supported on the under side of the frame 5 by any suitable form of supporting 125 means. At its rear end the slide 16 is formed with a bevel 33 and adjacent the bevel end 33 is a bevel lug 21 formed on the

under side of said slide 16. In the normal position of the parts the slide 16 is in the position shown in Fig. 3 relative to the table 5 and upon the rearward movement of the 5 table 5, on the operation of the handle 17, the slide 16 moves with it and maintains the same relative position until near the end of the rearward movement of the frame 5. As the frame 5 reaches its rearmost position 10 a lug 18 fast on the slide 16 at 41 will engage a flange 75 formed on the upper end of an arm 27 loosely pivoted on the shaft 8. Near the flange 75 the arm 27 is formed with an elongated slot 30 surrounding the shaft 15 29 for the purpose of limiting the movements of said arm. As the table moves rearward the lug 18 of the slide 16 will engage the arm 27 in the position shown in Fig. 3. At this point in the movement of the operating 20 handle 17 the rack teeth formed on the segment 9 will pass clear of the pinion 10 and consequently the movement of the table will be immediately discontinued. The hub 32 of the arm 27 at the point where it is pivotally mounted on the shaft 8 is formed with a cut away portion 42 into which projects a lug 31 rigidly mounted on the shaft 8. When the parts are in the position shown in Fig. 3 it will readily be seen that upon the rock- 25 ing movement of the shaft 8 when the handle 17 is operated, the lug 31 will move in a clockwise direction and will have no effect on the arm 27 until near the end of the movement of the handle 17, and just at the 30 time the lug 18 engages the arm 27. Upon a continued movement of the lever 17 the lug 31 will engage the upper wall of the cut away portion 42 and thereby rock the arm 27 in a clockwise direction and, through 35 the medium of the flange 75 and lug 18, will move the slide 16 to the right relative to the table 5 as shown in Fig. 3, thereby causing the bevel lug 21 carried by said slide to engage the roller 22. When the slide 16 is 40 so moved and the lug 21 engages the roller 22, the plate 23 will be rocked thereby effecting a rocking movement of the shaft 24 and arms 25 to move the clamping member 6 away from clamping engagement with the 45 rear edge of the table 5.

During the movement of the slide 16 as just described, retrograde movement of the table 5 in the direction of movement of the slide 16 is prevented in the following manner. The segment 9 (Fig. 6) is formed with extensions 76 and 77 carrying pins 78 and 79 respectively. Fast on the shaft 29 is a plate 80 formed with a pair of notches 81 and 82 which are adapted to coöperate with the pins 78 and 79 carried by the extensions 76 and 77 of the segments 9. As shown in Figs. 6 and 7, when the main operating lever is at its home position the pin 79 is in engagement with the notch 82 formed in

the plate 80 and thus all movement of the 65 shaft 29, gear 12 and table 5 is prevented. Upon the movement of the lever 17 and shaft 8 in a clockwise direction it will readily be seen that an initial movement of the segment 9 is effected before the rack teeth 70 carried thereby engage the pinion 10 which is fast on the shaft 29. The pin 79 will remain in the slot 82 during movement of the segment 9 until the rack teeth have fully engaged the pinion 10 when the pin 79 will 75 pass out of the notch 82 as soon as the rotation of the pinion 10 begins.

Near the end of the clockwise movement of the lever 17 the extension 76 of the segment 9 will come into play and the rotation of the pinion 10 and shaft 29 will cease as soon as the rack teeth formed on the segment 9 have passed the pinion 10. At this point the shaft 29 will have made slightly more than two complete rotations in a counter-clockwise direction and the notch 81 formed in the plate 80 will have been brought to the position directly in line with the pin 78 carried by the extension 76 of the segment 9. Therefore upon the continued movement of the lever 17 in a clockwise direction the pin 78 will pass into the notch 81 and it is just at this time that the lug 31 on shaft 8 engages the upper wall of the cut away portion 42 on the hub of arm 95 27, and though the slide 16 is then moved to the right in Fig. 3, retrograde movement of the table 5 is prevented as the pin 78 will then be moving in the notch 81. As the slide 16 moves to the right the under 100 flattened side of the bevel lug 21 will pass above the roller 22 and thereby hold the clamping member 6 in position of disengagement.

Upon the completion of the clockwise 105 movement of the lever 17 the said lever is adapted to be moved backward in a counter-clockwise direction to the normal position shown in Fig. 7 and during this movement of the lever 17 the action of the parts is exactly in the reverse. The segment 9 will be rocked in a counter-clockwise direction and just at the time the rack teeth formed thereon are about to engage the pinion 10 on the shaft 29 the pin 78 carried by the extension 110 76 will pass out of engagement with the notch 81 of the plate 80 thereby releasing the shaft 29 and permitting rotation thereof in a clockwise direction during the counter-clockwise movement of the lever 17. As 115 the lever 17 and gear 12 are so moved the table 5 will be moved to the right as shown in Figs. 1, 3 and 4, or forward in the practical use of the machine, until it reaches its inner home position, when the rack teeth 120 carried by the segment 9 will pass out of engagement with the pinion 10 and the pin 79 carried by the extension 77 will again enter

the notch 82 formed in the plate 80, thereby again locking the shaft 29 and table 5 in normal position. The latter, however, is effected during the excess movement of the lever 17 after the rack teeth of the segment 9 have been disengaged from the pinion 10, during which excess movement the clamping member 6 will again become effective to clamp the several strips to the frame 5. As the table 5 reaches its normal position a lug 19 carried by the slide 16, will engage the flange 75 of the arm 27. At this point the lug 31 on the shaft 8, which is moving in a counter-clockwise direction, will engage the lower wall of the cut away portion 42 in the hub 32 of the arm 27 and thereby immediately move the arm 27 in a counter-clockwise direction. This will effect movement of the slide 16 back to the left relative to the table 5 as shown in Fig. 3, and any movement of the table 5 to the left, as shown in said figure, will be prevented by reason of the engagement of the pin 79 with the notch 82. Upon movement of the slide 16, as just described, the bevel lug 21 will pass away from above the pin 22 on the plate 23 and the rear bevel end 33 of said slide 16 will engage the roller 34 and thereby rock the plate 23 in a counter-clockwise direction, as shown in Fig. 3. This will move the clamping member 6 to clamping position as shown in said Fig. 3.

As it is sometimes desired to place new rolls of paper in the machine it is necessary to provide some manually operated device for operating the clamping member 6 without operating the machine. This mechanism is shown in Fig. 4 and comprises simply a lever 43 which is pivoted loosely on the shaft 40 24 and has formed in its hub a notch 44 which surrounds a pin 45 carried on the rear end of the slide 16. It will readily be seen that when the parts are in normal position the lever 43 may be manipulated to move the slide 16 in either direction so as to move the clamping member 6 into or out of clamping position.

The form of supporting means for the supply rolls 1, 2 and 3 shown in Figs. 1, 2 and 5 comprises a plate 53 formed with downwardly extending arms 54 carrying at their lower ends bearings 50 which are adapted to project into the cores 51 of the paper rolls. The frame plate 53 is pivotally mounted on a shaft 48 and is formed with bearing hubs 49. The shafts 48 extend across between the side frames of the machine and as shown in Fig. 1 the bearing hubs 49 may be formed with elongated slots 52 surrounding said shafts 48 to permit free movement of the supporting frames. This form of supporting means is very simple, as will readily be seen, and the arms 54 may be bent toward one another to provide tension

to prevent any unnecessary unrolling of the record strips from the supply rolls.

A modified form of adjustable supporting means is shown in Figs. 7 and 8. This form of adjustable means comprises supporting members 85 and 86 which are pivotally fastened at 87 and 88 to the base 89 of the machine. The supports 85 and 86 are formed of spring material and carry at their upper ends similarly formed bearings 50 which project into the cores of the paper rolls. The inwardly projecting ends of the supports 85 and 86 are fast to screws 90 and 91 which project through holes formed in the base plate 89 of the machine and are provided on their lower ends with wing nuts 92 and 93. It will readily be seen that by an adjustment of the wing nuts 92 and 93 the tension of the spring supports 85 and 86 may be varied so as to hold the rolls against accidental movement and thereby prevent an unnecessary unrolling of the record strips.

The writing platform 35 is formed of light sheet metal or any other desired material and may be mounted in the manner shown in Fig. 3. When the platform 35 is formed in the manner shown in Fig. 3 it comprises merely the main body plate which rests on the side frames of the machine and is supported just above the sliding frames 5. The table 35 may be pivoted at its forward end as at 46 so as to facilitate access to the inner parts of the mechanism.

In order to hold the record strips down on the writing platform there is provided a main cover plate 94 which is pivoted at 95 to the carbon paper receptacle 7 as shown in Figs. 2 and 8. When mounted in this manner it will readily be seen that it serves the purpose of a lid for the receptacle 7 and also as a means for holding the record material flat on the writing platform. The plate 94 is adapted to extend across the entire machine and, of course, is formed with cut away portions to permit the making of written entries on the original record strip. At its left hand end the plate 94 may be provided with locking lips 96 which may be formed to snap down over a flange on the upper edge of the left hand side frame of the machine.

Carried by the under rear edge of the plate 94 is a light leaf spring 97 (see Fig. 3) which extends rearwardly and downwardly and presses lightly on the strips of record material above the rear edge of the writing platform 35. The purpose of the spring 97 is to prevent any accidental retrograde movement of the record strips during the return movement of the feeding frame 5 when the clamping member 6 is out of clamping position.

It will be noted by reference to the figures

that the frame of the machine comprises a pair of side frames 37 which are supported by the shaft 8 which, as hereinbefore mentioned, is mounted in the pair of standards 5 formed on the base of the machine. Rigidly mounted on each of the side frames 37, is a stud 98 which normally bears against the right hand sides of said standards as shown in Fig. 1. The purpose of so 10 constructing the machine is to enable a rocking movement of the entire machine except the base and shaft 8 about the point 8 so as to cause the writing platform to assume a vertical position in order to facilitate the 15 placement of rolls 1, 2 and 3 when any one of the same becomes exhausted. As the frame 5 is locked against movement by the pin 79 when the parts are in normal position, it will readily be seen that no relative 20 movement between the parts will be effected when the table is swung to a vertical position and therefore the lever 17 and its co-operating parts are moved as a unit and will not be relatively displaced. Consequently 25 when the table is swung upward the shaft 8 will rock with it.

The general operation of the machine is as follows: When it is desired to place a supply of paper in the machine it is necessary 30 to mount the rolls 1, 2 and 3 on the form of supporting means provided and to draw the ends thereof upward about the rollers 4. When filling the machine in this manner it is, course, necessary to rock the cover plate 35 94 out of normal position so as to permit the placing of the record strip directly on the table 35. When the record strips have been brought upward about the rollers 4 they are then placed flat on the table 35 with the 40 transfer material interposed between the various sheets. The strips are then passed to the rear end of the machine, that is, to the left in Fig. 1, and beneath the clamping member 6. As the clamping member 6 is 45 normally in clamping position as hereinbefore described, it is necessary to rock the lever 43 in a counter-clockwise direction shown in Fig. 4 to move the slide 16 to a position in which it will disengage the 50 clamping member. The ends of the record strips may then be inserted beneath the clamping member 6 and as soon as the forms on the record strips have been positioned to register correctly, the lever 43 is 55 rocked in a clockwise direction to move the slide 16 to a position wherein the clamping member 6 will again be rendered effective. It will be noted that the clamping member 6 is formed with a bevel cutting edge on the 60 rear edge to permit of severance of the portion of the record strip which projects beyond the clamping member. The machine is then ready for operation. When a written entry is made on the original record strip,

which is the top strip appearing on the writing table, said entry will be transferred by the transfer material to both the duplicate and the triplicate strips. The lever 17 is then drawn toward the operator, which movement will rock the shaft 8 in a clockwise direction. The first part of the movement of the lever 17 in a clockwise direction is idle as it is necessary to withdraw the pin 79 from the notch 82. As soon as the disengagement has been effected the rack 75 teeth formed on the segment 9 will have engaged the pinion 10 and during the continuing movement in a clockwise direction of the operating lever gears 12 and 13 will be rocked in a counter-clockwise direction causing the feeding table to be projected rearwardly. Just as the table reaches its rear-most position the rack teeth formed on the segment 9 will have passed the pinion 10 and consequently no rotation of the shaft 29 will 80 be effected during the continuing movement of the lever 17 in a clockwise direction. As soon as the parts reach this point in their operation, the pin 78 will pass into the notch 81 thereby locking the gear connections between the operating mechanism and the feeding frame against movement. This it will readily be seen will prevent any dislodgment of the feeding frame during the continued movement of the operating mechanism and will also hold the pinion 10 in a position wherein it will correctly mesh with the rack formed on the segment 9 as soon as it is again engaged thereby. During the continued motion of the lever 17 just above 95 100 described, the arm 27 will be rocked in a clockwise direction and caused to move the slide 16 carried by the feeding frame toward the operator, or to the right in Fig. 3, thereby disabling the clamping member. As soon as the return movement of the lever is effected in a counter-clockwise direction, the pin 78 will pass out of the notch 81 and the rock teeth formed on the segment 9 will immediately engage the pinion 10 and rotate the 110 shaft 29 and gears 12 and 13 in a clockwise direction, thereby carrying the feeding frame back to normal position. As soon as the feeding frame reaches its inner home position the rack teeth of the segment 9 will 115 again become disengaged from the pinion 10 and the gear connections will again become locked by the engagement of the pin 79 with the notch 82 of the plate 80. The lever is then given a slight final movement independent of any movement of the table and during said movement the arm 27 will be rocked in a counter-clockwise direction to cause its flange 75 to engage the lug 19 on the slide 16 whereby to move the latter rearwardly again to render the clamping member 6 effective. The part of the record strip which has thus been fed from the machine 120 125

by the above operation may be severed from the body portion of the record strip by drawing it taut across the bevel cutting edge formed on the clamping member 6, as hereinbefore described.

While the form of mechanism herein shown and described is admirably adapted to fulfil the objects primarily stated, it is to be understood that it is not intended to confine the invention to the one form of embodiment shown and described herein, as it is susceptible of embodiment in various forms, all coming within the scope of the claims which follow.

15. What is claimed is:—

1. In a machine of the class described, the combination with a reciprocatory feeding mechanism for record strips, of operating devices having a constant movement at each operation, means whereby the feeding mechanism is reciprocated during certain parts only of the movement of the operating mechanism, and devices for locking the feeding mechanism against movement during the other parts of the movement of the operating mechanism.

2. In a machine of the class described, the combination with a reciprocatory feeding mechanism for record strips, of a reciprocating operating mechanism for reciprocating said feeding mechanism, means whereby the operating mechanism has a movement in each direction slightly in excess of the movement of the feeding mechanism, and means for locking the feeding mechanism in adjusted position during said excess movement of the operating mechanism.

3. In a machine of the class described, the combination with a reciprocatory feeding mechanism for record strips, of a reciprocating operating mechanism for reciprocating said feeding mechanism, means whereby the operating mechanism has a movement in each direction slightly in excess of the movement of the feeding mechanism, and means controlled by said excess movement of the operating mechanism for locking the feeding mechanism in adjusted position during said excess movement.

4. In a machine of the class described, the combination with a reciprocatory feeding mechanism for record strips, of a reciprocating operating mechanism for reciprocating said feeding mechanism, means whereby the operating mechanism has a movement in each direction slightly in excess of the movement of the feeding mechanism, and means carried by the operating mechanism for locking the feeding mechanism in its positions of adjustment during the said excess movement of the operating mechanism.

5. In a machine of the class described, the combination with a reciprocatory feeding mechanism for record strips comprising

a sliding frame having racks formed thereon, of gear connections constantly in engagement with said racks, a reciprocatory operating device, and an operating segment operated thereby during its entire reciprocating movement and constructed to operate said gear connections during a portion of said movement.

6. In a machine of the class described, the combination with a reciprocatory feeding mechanism for record strips comprising a sliding frame having racks formed thereon, of gear connections constantly in engagement with said racks, a reciprocatory operating device, an operating segment operated thereby during its entire reciprocating movement and constructed to operate said gear connections during a portion of said movement, and means controlled by the operating mechanism for preventing movement of the feeding means during the remainder of said movement.

7. In a machine of the class described, the combination with a reciprocatory feeding mechanism for record strips comprising a sliding frame having racks formed thereon, of gear connections constantly in engagement with said racks, a reciprocatory operating device, an operating segment operated thereby during its entire reciprocating movement and constructed to operate said gear connections during a portion of said movement, and means controlled by the operating mechanism for locking said gear connections during the remainder of said movement.

8. In a machine of the class described, the combination with a reciprocatory feeding mechanism for record strips comprising a sliding frame having racks formed thereon, of gear connections constantly in engagement with said racks, a reciprocatory operating device, an operating segment operated thereby during its entire reciprocating movement and constructed to operate said gear connections during a portion of said movement, and means controlled by said segment for preventing movement of the feeding means during the remainder of said movement.

9. In a machine of the class described, the combination with a reciprocatory feeding mechanism for record strips comprising a sliding frame having racks formed thereon, of gear connections constantly in engagement with said racks, a reciprocatory operating device, an operating segment operated thereby during its entire reciprocating movement and constructed to operate said gear connections during a portion of said movement, and means controlled by said segment for locking said gear connections during the remainder of said movement.

10. In a machine of the class described,

- the combination with a reciprocatory feeding mechanism for record strips comprising a sliding frame having racks formed thereon, of gear connections constantly in engagement with said racks, a reciprocatory operating device, an operating segment operated thereby during its entire reciprocating movement and constructed to operate said gear connections during a portion 5 of said movement, a notched plate fast to said gear connections, and pins carried by said segment and coöperating with said plate to lock said gear connections during the remainder of said movement.
11. In a machine of the class described, the combination with a reciprocatory feeding mechanism for record strips comprising a sliding frame having racks formed thereon, of gears constantly in engagement with 10 said racks, a driving element having a reciprocatory movement and formed with a rack portion of sufficient length to engage and drive said gears during a portion only 15 of the movement in each direction of the driving element, and means for locking the aforesaid sliding frame against movement while the rack on the driving element is disengaged from the aforesaid gears.
12. In a machine of the class described, the combination with a reciprocatory feeding mechanism for record strips comprising a sliding frame having racks formed thereon, of gears constantly in engagement with said racks, a driving element having a 20 reciprocatory movement and formed with a rack portion of sufficient length to engage and drive said gears during a portion only 25 of the movement in each direction of the reciprocatory driving element, and devices whereby the operating member locks the sliding frame against movement during the other portions of the movement of said member.
13. In a machine of the class described, the combination with a feeding mechanism 30 for record strips comprising a sliding frame, of a reciprocatory operating mechanism, devices intermediate the operating mechanism and the sliding frame constructed to impart a feeding stroke and a restoring stroke to the frame during an operation of the operating mechanism, means for locking the frame against movement at the end of each 35 of its strokes, means for clamping the record strips to the frame, said means to be rendered effective at the end of the restoring stroke and ineffective at the end of the feeding stroke, and means actuated by the operating mechanism for operating said 40 clamping device while the sliding frame is locked against movement at the ends of said strokes.
14. In a machine of the class described, the combination with a feeding mechanism 45 for record strips comprising a sliding frame, a rack formed on said frame, an operating device, gear connections intermediate the operating device and rack and constructed to reciprocate said frame during a portion of each operation of the machine whereby said frame will receive a feeding stroke and a restoring stroke, a clamping device carried 50 for record strips comprising a sliding frame, 65 a rack formed on said frame, an operating device, gear connections intermediate the operating device and rack and constructed to reciprocate said frame during a portion of each operation of the machine whereby said frame will receive a feeding stroke and a restoring stroke; a normally effective clamping device carried by the frame, and means carried by the frame and actuated by the operating device during its movement independent of the frame whereby said clamping device will be rendered ineffective between the strokes of the frame and effective at the end of the restoring stroke thereof.
15. In a machine of the class described, the combination with a reciprocatory feeding mechanism for record strips, of an operating mechanism, connections intermediate said mechanisms for intermittently operating said feeding mechanism during portions of a single operation of the operating mechanism, and means for locking the feeding mechanism in its moved positions during the remaining portions of an operation.
16. In a machine of the class described, the combination with a reciprocatory feeding mechanism for record strips, of an operating mechanism, connections intermediate said mechanisms for intermittently operating said feeding mechanism during portions of a single operation of the operating mechanism, means for locking the feeding mechanism in its moved positions during the remaining portions of said operation, a clamping device carried by the feeding mechanism, and means also carried by the feeding mechanism and actuated by the operating mechanism independently of the feeding mechanism for rendering the clamping device effective and inoperative when the feeding mechanism is locked.
17. In a machine of the class described, the combination with a feeding mechanism for record strips comprising a sliding frame, of a normally effective adjustable clamping device carried by said frame, an operating device constructed to reciprocate said frame whereby the latter will receive a feeding stroke and restoring stroke at each operation of the operating device, and means operable independently of an operation of the operating device for rendering the clamping device effective or ineffective at will.
18. In a machine of the class described, the combination with a feeding mechanism for record strips comprising a sliding frame, a rack formed on said frame, an operating device, gear connections intermediate the operating device and rack and constructed to reciprocate said frame during a portion of each operation of the machine whereby said frame will receive a feeding stroke and a restoring stroke, a clamping device carried 120

- by the frame, and means operable independently of an operation of the operating device for rendering the clamping device effective or ineffective at will.
- 5 19. In a machine of the class described, the combination with record strip feeding devices comprising a sliding frame, of an operating mechanism constructed to impart a reciprocatory movement to said frame 19 but having movements independent thereof, means for locking the frame against movement during such independent movement of the operating mechanism, a clamping device for the record strips carried by the sliding frame, and means actuated by the operating mechanism while the sliding frame is locked against movement for rendering the clamping device ineffective and effective.
- In testimony whereof I affix my signature in the presence of two witnesses.
- FREDERICK L. FULLER.
